UNITED STATES PATENT OFFICE.

WYATT T. SEBREE, OF LOUISVILLE, KENTUCKY.

DESIGN FOR AN ADVERTISING-BOARD.

49,937.

Specification for Design.

Patented Nov. 21, 1916.

Application filed September 23, 1916. Serial No. 121,892. Term of patent 7 years.

To all whom it may concern:

Be it known that I, WYATT T. SEBREE, a citizen of the United States, residing at Louisville, in the county of Jefferson and State of Kentucky, have invented a new, original, and ornamental Design for Advertising-Boards, of which the following is a specification, reference being had to the accompanying drawing, forming part thereof.

The figure is a plan view of an advertising board, showing my new design.

I claim:

The ornamental design for an advertising board, as shown.

WYATT T. SEBREE.

Witnesses:

M. H. THATCHER,
M. L. HEITZ.
